UNITED STATES PATENT OFFICE.

JAMES H. DEAN, OF CHICAGO, ILLINOIS, ASSIGNOR TO EVA C. HERSEY, OF ST. PAUL, MINNESOTA.

VOTING-MACHINE.

No. 911,552.

Specification of Letters Patent.

Patented Feb. 2, 1909.

Application filed May 23, 1907. Serial No. 375,201.

To all whom it may concern:

Be it known that I, JAMES H. DEAN, a citizen of the United States, and a resident of Chicago, county of Cook, and State of Illinois, have invented certain new and useful Improvements in Voting-Machines, of which the following is a specification.

The invention relates to voting machines and seeks to provide improved means for insuring accurate operation of the machine.

The invention comprises broadly a mechanical device or devices adapted to register with the counters when in zero position so that it is not necessary to depend upon the visual inspection of the counters in order to ascertain whether or not all of the counters are at zero.

The invention further comprises the combination of locking means with such a registering device or devices whereby it is impossible to operate the machine unless all of the counters are at zero.

Numerous forms of mechanical registering devices and locking means may be employed and adapted to different forms of machines without departure from the essentials of the invention.

The details of structure adapted for the practice of the improvements and the selected style of the machine shown by the drawings will appear from the description following and the invention be thereafter more particularly pointed out by the appended claims.

The invention is shown as applied to the form of voting machine set forth in a prior application filed by me October 30, 1905, Serial No. 285,045, but it will be understood that the improvement may be applied to other forms of machine.

In the drawings, Figure 1 is a view in elevation showing the face of the machine with some of the counters or registers concealed and others exposed to view. Fig. 2 is a vertical section through the machine on the line 2-2 of Fig. 3. Fig. 3 is a plan view of one of the unit sections of the machine with certain parts shown in section. Fig. 4 is a cross section on the line 4-4 of Fig. 3. Fig. 5 is a rear elevation of the machine with a back cover plate shown in section to show the registering plate of the zero mechanism. Fig. 6 is a plan view of the bottom part or section of the machine with the back plate

and registering plate shown in section. Figs. 7, 8 and 9 are cross sections on the line 7-7, 8-8 and 9-9 respectively of Fig. 6. Fig. 10 is a plan section on the line 10-10 of Fig. 7 with parts in shifted position. Fig. 11 is a detail section on line 11-11 of Fig. 7.

The machine, as in the prior application referred to, is made up of units or sections, each unit frame or channel 1 having a set of voting mechanisms for all of the candidates for a single office, the number of unit sections required for any given election being placed one upon the other and connected together with the top and bottom parts 2 and 3 by through bolts 4. It will be understood however, that the present invention is not limited to a machine built up in this way.

Many of the features in the form of machine shown are similar to that set forth in the application above referred to, and will be but briefly described in this application. The machine as a whole is carried at a suitable height above the floor upon legs or supports 5 secured to the base part 3 at their upper ends. The upper portions only of these legs or supports are shown in the drawings.

A short, vertical shaft 6 (see Fig. 2) is journaled in the upper, central portions of the top frame or part 2 and to this shaft is centrally fixed a curtain supporting arm 7 which carries a suitable booth or curtain and which is rotated through a half revolution by a voter to inclose the front of the machine when he desires to cast his ballot and which is again rotated through a half revolution by the voter to complete the operation of the machine and again expose its face. The lower end of the shaft 6 within the top frame or part 2 carries a sprocket wheel 8 connected by a chain 9 to a sprocket 10 journaled on a stud 11 at one end of the top frame or part 2. Sprocket 11 is connected by a coupling 12 to the upper end of a vertical motor shaft 13. This shaft is square in section (see Fig. 3) and extends through similarly shaped openings in the operating, rotary cam members 14 journaled in the left hand end of each office section. At its lower end, the shaft 13 engages square openings formed in the upper and lower ends of a collar or sleeve 15 (see Figs. 2, 6 and 10) rotatably mounted in the left hand end of the bottom part or frame 3. A ratchet wheel 6^a on the lower end of the shaft 6 is ar-

ranged to be engaged by a spring-held pawl 6^b so that the shaft 6 and the motor shaft 13 can be rotated in one direction only.

Each unit frame is provided with a number 5 of counters, four in number in the form shown. Preferably, seven or eight of these counters are employed in each section. These counters are all duplicates and each 10 comprises units, tens and hundreds wheels 16, 17 and 18. (see Fig. 3) the numbers whereon may be viewed through openings 19 (see Fig. 1) in the front walls of the office sections. These wheels or dials have hubs 20 mounted upon spindles 21. These spindles are 15 arranged in sets of three, as shown, one set for each counter, and are suitably journaled in the front and back walls of the office sections. The hubs of the units and tens wheels are provided with single toothed gears 22 engaging 20 intermittent gears 23 on the hubs of the tens and hundreds wheels, respectively, to transmit the motion from the units to the tens wheels and from the tens to the hundreds wheels. The hubs of the tens and 25 hundreds wheels are provided with locking wheels 24 engaging suitable mutilated locking surfaces 25 on the hubs of the units and tens wheels, respectively. These counters are in all respects similar to those set forth in 30 the prior application referred to, except that the hubs of all the wheels are rigidly secured to the supporting pins or shafts 21.

The push keys 26 for the voter, extend 35 through the front wall of the machine casing and within the sections are connected to slides 27 mounted upon the pins or shafts 21 of two adjacent sets. The cylindrical actuator 28 is connected to shift longitudinally with the key but is rotatable thereon. It 40 engages with a locking wheel 29 on the hub of the units wheel and is provided with a single tooth 30 which may be shifted into and out of line with an intermittent gear 31 on the hub of the units wheel. Each slide 27 is 45 provided with a pin 32 arranged to be engaged by the lugs or cams on the locking and restoring bar 33. The slides are also provided with arms 34 (see Fig. 4) having spreaders 35 on their rear ends which coöperate 50 with the interlocking blocks 36 sliding on the bottom of the unit frame or section. The actuators are each provided with a gear 37 and the gears of all the actuators in any one section are operated by a rack 38 mounted 55 ed to slide upon the bottom of the section.

The locking and restoring bar 33 and the rack bar 38 are each provided at the left hand end of the office section with a head 39 having lugs or shoulders 40 and 41 which are 60 operated upon pins 42 and 43 in the rotary cam members 14 to reciprocate the locking and restoring bars. Before the voter is admitted to the machine the locking bars 33 are in the position shown in Fig. 3 so that the 65 lugs thereon engage the pins 32 to lock all

of the keys in their inoperative position. By swinging the arm 7, shafts 6 and 13 are given a half revolution and the voter is enclosed by the booth or curtain hung from the arm 7. This half revolution of the shaft 70 13 will correspondingly shift the cams 14 and the bars 33 of the several office sections to unlock the keys. The voter may then cast his ballot by pressing in the keys opposite the names of those candidates for whom he desires to vote, so as to bring the single toothed actuators 30 in line with the intermittent gears 31 on the units wheel of the corresponding counters. The interlocking blocks are arranged to prevent the operation 80 of more than the proper number of keys. When the voter leaves the booth, shafts 6 and 13 and the cams 14 will again be given a half revolution and the racks 38 operated so that the counters corresponding to the keys 85 which have been placed in voted position, will be advanced one step. The bars 33 are also operated to restore and lock the keys in position in readiness to admit the next voter. 90

The openings 19 in the front of the machine casing through which the counters are read, are concealed during an election by the name plates 44, each of which bears the names of candidates for the several offices 95 to be filled, usually those of a single party. These plates 44 are held in place at their upper ends by pins or lugs 45 projecting from the top frame or part 2 and at their lower ends by projecting T-heads 46 on the outer 100 ends of shafts 47 journaled in the lower base part 3. These heads, when in horizontal position indicated in dotted lines in Fig. 1, project through horizontal slots in the lower ends of the name plates 44 into recesses or 105 members formed in the base part of the handles 48 at the lower ends of the name plates, as shown in Fig. 9. By rotating the shafts 47 and T-heads 46 through a quarter revolution in the position shown in full lines 110 in Fig. 1, the name plates are securely held to conceal the counters. The shafts 47 and heads 46 are shifted by a common connecting bar or plate 49 (see Figs. 2, 6, 9 and 10 inclusive) which extends lengthwise within 115 the lower part or base section 3, and is provided with openings through which the shafts 47 extend. Crank arms 50 on the shafts are connected by pins 51 to the connecting bar or plate 49, and one of these 120 arms is extended to form a handle 52 which projects through a slot 53 in the bottom of the base section. This arm is provided with a quadrant 54 having openings 55 therein by which the arm may be held by means of a 125 pad-lock 56 in one or the other of its extreme positions. In the position shown in full lines in the drawings, the shafts 47 and heads 46 thereon are in position to lock the name plates and conceal the counters. At 130

the end of the election the judge or other official in charge, may release the pad-lock 56 and shift the shafts and T-heads 46 to release the name plates and thus expose the 5 count.

At one end of the base section is a locking bolt 57 mounted to slide longitudinally in a block 58 into and out of a slot 59 in the sleeve 15. When the shafts 47 are shifted 10 to release the name plates and thus expose the count, the plate 49 moves to the left and shifts the locking bolt 57 into the slot 59 of the sleeve 15. This sleeve is keyed on the motor shaft 13 so that when it is locked 15 the machine is also locked against operation and no further operation of the machine is thus permitted after the count is once exposed. This locking bolt 57 is held against accidental displacement in one or the other 20 of its extreme positions by a spring-held stud 60 (see Fig. 7) mounted in a socket in the block 58 in which the bolt slides and arranged to engage with one or the other of two depressions in the side of the bolt. 25 The parts and mode of operation thus far described are similar to those set forth in the prior application referred to and need not be more fully set forth here.

As stated, the wheels of the counters are 30 rigidly secured upon the shafts or pins 21 and these project through the machine casing and disks 61 (see Figs. 3, 4 and 5), each having a single notch 62 in its edge, are fixed to the rear ends of the pins or shafts 21. 35 The notch 60 of each disk corresponds to the zero position of the counter wheel to which it is fixed. That is to say, when any counter wheel is at zero the notch 62 in the corresponding disk 61 will be directly above 40 the pin or shaft 21 and in the position shown in Fig. 5. A rectangular locking or registering plate 63 is mounted on the rear of the machine in a set of guide blocks 64 that are fixed to the rear faces of the top and base 45 parts of the machine and provided with vertical guide slots engaging the side edges of the rectangular plate 63 adjacent the top and bottom thereof, so that the plate is guided to shift in vertical direction. A lug 65 50 fixed to and rearwardly projecting from the base part 3 of the machine extends through a notch 66 in the lower edge of the plate 65. A depending hook or handle 67 is secured to the lower edge of the plate 65 and is provided with a projecting lug 68 extending beneath the lug 65. The vertical movement of the registering or locking plate 63 is limited 55 by the engagement of the lug 68 and the bottom part of the notch 66 with the fixed lug 65. The registering plate is normally held in its uppermost position by a pair of spiral springs 69 which engage the lower edge of the plate and are set within suitable sockets in a pair of brackets 70 fixed to the 60 rear face of the base portion 3. In this nor-

mal position, the lug 68 on the hook or handle 67 engages the fixed lug 65. The plate is provided with a series of inwardly projecting registering pins 71 which correspond in number with the counter wheels of the 70 machine and which are arranged directly above the shafts or pins 21 whereon the counter wheels are mounted. It is obvious that, if all of the counter wheels of the machine are at zero and the notches 62 in 75 the corresponding disks all face upwardly, as shown in Fig. 5, the registering plate or disk 63 may then be depressed or pulled down by means of the handle 67 to bring the registering pins 71 thereon into engagement with the notches 62 of the disks. If however, any one or more of the counter wheels are not at zero, the notches 62 on the corresponding disk will not be in line with the adjacent registering pins and the plate 80 cannot be pulled down or depressed. 85

A flanged back plate or casing 72 in the form shown, is arranged over the registering plate 63. This casing engages a pair of pins 73 at its upper edge that are fixed upon 90 the rear face of the top part 2. The lug 65 upon the bottom part 3 of the machine projects through an opening in the casing 72 and the latter is secured against displacement by a pad-lock 74 engaging an opening 95 in the lug 65. The key of the lock 74 is retained by the city clerk or other officer having charge of the entire election so that no unauthorized person can remove the back plate 72 and tamper with the registering 100 plate 63. The hook or handle 67 on the plate projects through a slot 75 in the bottom flange of the casing.

Such a mechanical registering device could be employed for the purpose of ascertaining 105 whether or not all of the counters of the machine were at zero instead of relying solely upon the visual inspection of the counters. It is well known that in the visual inspection of a large number of counters in a voting 110 machine that one or more of the counters which are not at zero, may be easily overlooked and such a mechanical registering device could be employed without further mechanism for the purpose of ascertaining 115 whether or not the counters of the machine were at zero. Preferably, however, the locking or registering device is connected or interlocked with means for locking the machine against operation so that it is impossible to 120 set the machine for operation if any of the counters are not in zero position.

The counter registering device, for determining whether or not the counters are at zero, may be arranged to directly control 125 means for locking the machine against operation, but, in the form shown, it has direct control over the releasing means for the lock so as to indirectly control the latter. The releasing device for the bolt 57 in the form of 130

a slide 76 (see Figs. 6, 7 and 10) is mounted to move from front to rear of the machine above the bolt 57 in a guide-way formed in the upper portion of the block 58. The slide is provided on its under side with a cam lug 77 having an inclined face arranged to engage the inclined face of an upwardly projecting lug 78 on the end of the bolt 57.

When the shaft 47 and bar 49 are shifted 10 to expose the vote, the lock 57 is moved by the bar 49 from the position shown in Figs. 2 and 6 to that shown in Fig. 10 to lock the machine against further operation. At the same time the engagement of the cam lug 78 15 on the locking bolt with the cam lug 77 on the releasing slide will shift the latter rearwardly from the position shown in Fig. 6 to that shown in Fig. 10. The bolt may be released and the machine unlocked by forcing 20 the releasing slide 76 back toward the front of the machine. This is accomplished by means of a suitable pin or like instrument, inserted in openings 79, 80 and 81 formed respectively in the back plate 72, the registering plate 63 and the rear wall of the bottom part 3. The opening 79 in the back plate 72 and the opening 81 in the rear wall of the machine frame are opposite each other and the opening 80 in the registering plate 63 30 is in line with the openings 79 and 81 when the releasing plate is in its normal, uppermost position. The opening 81 is however, normally closed to prevent the insertion of a pin or other unlocking instrument by a sliding guard plate or bar 82 mounted to slide from side to side of the machine in a suitable guide-way formed in the block 58 just in front of the rear wall of the frame. This sliding guard plate or bar is provided with an 35 opening 83 which, in the normal position of the guard, shown in Fig. 6, is out of line with the opening 81. When the guard is shifted to the position shown in Fig. 10, the opening 83 is brought opposite the opening 81 and the pin or other unlocking instrument may be inserted to force the releasing slide 76 toward the front of the machine and retract the bolt 78, thus unlocking the machine. A spring-held stud or pin 82^a mounted in a socket in 40 the block 58 is adapted to engage with one or the other of two depressions in the side of the guard 82 to hold the latter in one or the other of its shifted positions.

The guard 82 is shifted to bring the opening 83 therein into register with the opening 81 in the wall of the casing by means of a lug or pin 84 fixed to the registering plate 63 and projecting inwardly therefrom through a vertical slot 84^a in the rear wall of the base 45 part or frame 3. When the registering plate is pulled down the pin or lug 84 thereon engages an inclined cam face 85 on the end of the sliding guard 82 and shifts it from the position shown in Fig. 6 to the position 50 shown in Fig. 10. Since the registering

plate cannot be depressed except when the wheels of the counters are all at zero, the guard 82 cannot be shifted and the machine cannot be unlocked.

The projecting pin or lug 84 extends inwardly over the rear end of the locking block 57 when the latter is in its retracted or inoperative position shown in Fig. 6, so that it is impossible to depress the registering plate 63 70 to shift the pins 71 thereon into the notches 75 62 of the disks 61 while the machine is unlocked. It is also impossible to unlock the machine while the plate 63 is in its depressed condition with its pins 71 in the notches 62 of the disks 61 since the lug or pin 84 on the 80 plate is then in line with the bolt 57 and prevents the releasing shift thereof and since the opening 80 in the releasing plate is then out of line with the holes 79 and 81, so that the pin or other instrument cannot be inserted to 85 shift the releasing slide 76. It is thus impossible under any circumstances to operate or attempt to operate the machine while the pins 71 of the registering plate are within the notches of the registering disks 61. This 90 effectually prevents any damage to the registering device through careless handling of the machine.

The sliding guard 82 is provided on its outer end with a head or forwardly projecting lug 86 which is adapted to engage with either one of a pair of recesses 87 in the sleeve or collar 15 on the operating shaft 13 and the guard 82 cannot be shifted to permit the release of the locking device unless the shaft 95 100 105 110 115 120 125 130 135 140 145 150 155 160 165 170 175 180 185 190 195 counters are exposed by removing the name plates 44 so that the judges and inspectors of election may see that the counters are at zero. The name plates cannot be removed 5 for this purpose without shifting the bar 49 which insures the setting of the bolt 57 to lock the machine if the latter is not already in its operative or locking position. The name plates 44 are then restored and locked 10 in place by means of the shifting T-heads 46 on the shafts 47. The registering plate 63 is then depressed to shift the sliding guard 82 to bring the opening 83 therein in register with the opening 81 in the machine casing. 15 The registering plate is then released and restored to normal position by the springs 69 and a pin or other unlocking instrument is thrust into the aligned openings 79, 80, 81 and 83 and the releasing slide 76 is 20 shifted to retract the locking bolt 57. This cannot of course be effected unless all of the counters of the machine are at zero, so that the election cannot be proceeded with until the machine is set in proper condition. As 25 stated, the shift of the guard 82 brings the lug 86 thereon into one of the depressions 87 on the sleeve or collar 15, so that the first operation of the machine restores the guard to its normal position and the unlocking in- 30 strument cannot again be inserted until the end of the election and until all of the counters have been first restored to zero position. At the end of the election, the name plates 44 are again removed to dis- 35 close the vote, and this removal necessitates the shift of the bar 49 and of the bolt 57 so that the machine is locked against further operation once the counters are exposed. To prepare the machine for a new election, 40 it is necessary to first restore all of the counters to zero position.

To permit the restoration of the counters to zero, the cylindrical locking surfaces of the actuators 28 are provided with mutilated 45 portions or depressions 88 (see Fig. 3) which, when brought opposite the teeth of the locking wheels 29, disconnect the counters and actuators and the former may then be restored to zero by means of a suitable key 50 or the like applied to the front squared ends of the pins or shafts 21 upon which the units wheels are mounted. Normally, the cylindrical locking surfaces of the actuators prevent any movement of the counters except 55 a step at a time through the medium of the teeth 30 thereon in the ordinary voting operation of the machine, as above described, and in the ordinary operation of the machine the mutilated portions 88 are never 60 brought opposite the teeth of the locking wheels 29. By shifting the rack bars 38 to an abnormal extent, the mutilated portions 88 may be brought opposite the locking wheels so as to disconnect the counters

and counter actuators. During the ordinary 65 voting operation of the machine however, the movement of the rack bars is limited and the abnormal shift thereof prevented by a vertical strip or bar 89 which engages lugs 90 mounted upon the heads of the rack bars 70 and projecting through slots in the front wall of the casing. This locking strip 89 is fixed to the inner face of the office name plate 91 which is removably mounted on the front of the machine (see Fig. 1). The upper 75 end of this plate 91 engages one of the pins 45 and its lower end sets over the lug 92 on the base portion 3 and a pad-lock 93 engaging the lug 92, prevents the removal of the name plate 91. The key of this lock is re- 80 tained by the city clerk or other proper official so that the name plate cannot be removed during the operation of the machine.

To prepare the machine for the next 85 election, the name plate 91 must be first removed, the rack bars abnormally shifted towards the right to disconnect the actuators and counters and the latter then restored to zero. To permit the abnormal 90 shift of the rack bars the operating pins 42 therefor on the collars 14, must be shifted through a quarter turn from the position shown in Fig. 3. This quarter turn is permitted by the elongated slot 59 (see Fig. 11) 95 with which the locking bolt 57 engages.

It should be noted that the operating mechanism which releases the keys for operation and restores and locks the same in normal position, the lock for the operating 100 mechanism and the registering plate which is adapted to interlock with all of the wheels of all of the counters only when the latter are in zero position, form a positive interlock between the keys and the counters 105 such that it is mechanically impossible to vote on the machine until the counters are first restored to zero position. The same devices form a positive interlock between the operating mechanism which governs the 110 operation of the counters and the counters themselves such that it is mechanically impossible to operate the counters until they have first been restored to zero position.

It is obvious that the details set forth may 115 be widely varied without departure from the broad scope of the invention.

Having described my invention, what I claim as new and desire to secure by Letters Patent, is:—

1. In a voting machine, the combination with a series of independently operable counters of a testing device common to and registering with all of said counters when the latter are at zero.
2. In a voting machine, the combination with a series of independently operable counters, each having a number of counter wheels

or disks, of a testing device common to and registering with all of said counters when all of said wheels or disks are at zero.

3. In a voting machine, the combination 5 with a series of independently operable counters, of a testing device common to all of said counters, said counters and said testing device being relatively movable and registering when all of said counters are at zero.

10 4. In a voting machine, the combination 10 with a series of independently operable counters, each having a number of counter wheels or disks, of a movable member common to all of said counters and arranged to register therewith when all of the wheels or disks thereof are at zero.

15 5. In a voting machine, the combination 20 with a series of independently operable counters, each having a number of wheels or disks, of a movable member common to all of said counters, said movable member and each of said counter wheels or disks having interengaging parts registering when all of said counter wheels are in zero position.

25 6. In a voting machine, the combination 30 with a series of independently operable counters, of a movable part, said counters and said movable part having interengaging members registering when all of said counters are in zero position.

35 7. In a voting machine, the combination 40 with a series of independently operable counters, each having a number of counter wheels, of a movable member common to all of said counters, said member and said counter wheels having interengaging pins and notched disks respectively registering when all of said counter wheels are in zero position.

45 8. In a voting machine, the combination 40 with a series of independently operable counters, each comprising a number of counter wheels, of shafts whereon said wheels are mounted, notched disks fixed to said shafts and a movable plate or member having pins registering with said notched disks in the zero position of said counter wheels.

50 9. In a voting machine, the combination 50 with a series of counters, of interlocking means arranged to mechanically and positively prevent the initial operation of said counters, except when the latter are at zero position.

55 10. In a voting machine, the combination 55 with a series of counters and operating mechanism therefor, of positive interlocking means interposed between said counters and operating mechanism arranged to compel the setting of said counters in zero position before they can be operated.

60 11. In a voting machine, the combination 60 with a series of independently operable counters and mechanism controlling the operation thereof, of positive interlocking devices between said counters and counter controlling mechanism compelling the setting of

said counters in zero position before they can be initially operated.

12. In a voting machine, the combination 70 with the counters and the counter controlling mechanism, of positive interlocking devices interposed between said counters and said controlling mechanism, whereby the initial operation of said counters is positively and mechanically prevented when any one of the same is not in zero position.

75 13. In a voting machine, the combination 80 with a series of independently operable counters and locking and restoring mechanism therefor, of positive interlocking devices interposed between said mechanism and said counters compelling the setting of the latter at zero position before said counters can be released for initial operation.

85 14. In a voting machine, the combination 90 with a series of counters and controlling mechanism therefor, of a lock for said counter controlling mechanism and positive interlocking devices interposed between said counters and said lock for preventing release from the latter except when said counters are all in zero position.

95 15. In a voting machine, the combination 100 with a series of counters and locking and restoring mechanism therefor, of a lock for said mechanism, and means mechanically interlocking with said counters and operable only in the zero position thereof controlling the release of said lock whereby said counters can only be released for initial operation when in zero position.

105 16. In a voting machine, the combination 105 with a series of counters and counter controlling mechanism, of a device mechanically interlocking with said counters when in zero position and means associated therewith for preventing the initial operation of said counters when one or more of the counters are out of zero position.

110 17. In a voting machine, the combination 110 with a series of counters and means for locking the same against operation, of a device mechanically interlocking with said counters when in zero position and means associated therewith for controlling said locking means.

115 18. In a voting machine, the combination 115 with a series of counters and a lock for holding said counters against operation, of a device mechanically interlocking with and movable when said counters are in zero position and a release for said lock controlled by said registering device.

120 19. In a voting machine, the combination 120 with a series of counters and operating mechanism therefor, of a lock for said operating mechanism, a releasing device for said lock and means mechanically interlocking with said counters when the latter are in zero position controlling the operation of said releasing device.

125 20. In a voting machine, the combination 130

with a series of counters and with a locking and restoring mechanism therefor, of a lock for said mechanism, a releasing device for said lock and a member mechanically interlocking with and movable when said counters are in zero position, said registering member controlling the operation of said releasing device.

21. In a voting machine, the combination 10 with a series of counters, of means for locking the counters against operation when exposed and means associated with said counters and locking means for preventing the further operation of said counters until 15 the latter have been returned to zero.

22. In a voting machine, the combination with a series of counters, of a lock for holding said counters against operation when exposed and interlocking devices between 20 said lock and counters for preventing the release of the latter except when the counters are in zero position.

23. In a voting machine, the combination with a series of counters, of a lock for holding 25 said counters against operation when exposed and a device registering said counters in zero position controlling the release of said lock.

24. In a voting machine, the combination 30 with a series of counters and means compelling the locking of said counters against operation when exposed and interlocking devices between said counters and locking means controlling the release of said locking 35 means when compelling the restoration of the counters to zero position for further operation.

25. In a voting machine, the combination with a series of counters, of means normally 40 preventing access to said counters and interlocking devices interposed between said means and said counters whereby access to said counters necessitates the resetting of the same to zero for any further operation.

45 26. In a voting machine, the combination with the counters, of means normally concealing said counters and interlocking devices interposed between said counter concealing means and said counters whereby the exposure of said counters necessitates the re-setting thereof to zero position for further operation thereof.

50 27. In a voting machine, the combination with a series of counters, of counter concealing 55 means, a lock controlled by said concealing means for holding said counters against operation when exposed and means interposed between said counters and said lock for preventing the release of the latter except 60 in the zero position of the counters.

28. In a voting machine, the combination with a series of counters, of counter concealing means, a lock controlled by said concealing means for holding said counters against 65 operation when exposed and a device regis-

tering with said counters in zero position controlling the release of said lock.

29. In a voting machine, the combination with a series of counters, of counter concealing means, a lock controlled by said concealing means for holding said counters against operation when exposed, a release for said lock and a device registering with and movable when said counters are in zero position controlling the release of said lock. 70

30. In a voting machine, the combination with a series of counters and counter operating mechanism, of means normally preventing access to the counters, a lock for said counter operating mechanism associated 80 with said means and set for operation when access is afforded to said counters, a release for said lock and a releasing device associated with said counters and registering therewith and movable in the zero position of the 85 counters for controlling the operation of said releasing device.

31. In a voting machine, the combination with the counters and counter operating mechanism, of a lock for said operating mechanism, means normally preventing access to said counters arranged to operate said lock when access is afforded to said counters and a device registering with said counters in zero 90 position controlling the release of said lock. 95

32. In a voting machine, the combination with a series of counters and controlling mechanism therefor, of a lock for said controlling mechanism, means normally concealing said counters arranged to operate said 100 lock and shift it to expose the same, a release for said lock and a device associated with said counters registering therewith and movable when the counters are at zero and means associated with said registering device controlling the release of said lock. 105

33. In a voting machine, the combination with a series of counters controlling the keys therefor, locking and restoring mechanism for said keys, of devices interposed between 110 said locking and restoring mechanism and said counters for preventing the release of said keys for initial operation, except when said counters are in zero position.

34. In a voting machine, the combination 115 with a series of counters and controlling keys therefor, of positive interlocking devices interposed between said keys and counters arranged to prevent the initial operation of said keys, except in the zero position of all 120 of said counters.

35. In a voting machine, the combination with a series of counters, controlling keys therefor, of locking and restoring mechanism for said keys, a lock for said mechanism and 125 a device mechanically interlocking with said counters when the latter are in zero position controlling the release of said lock.

36. In a voting machine, the combination with a series of counters, controlling keys 130

therefor, locking and restoring mechanism for said keys, a lock for said mechanism, means normally concealed in the counters arranged to set said lock when said counters 5 are exposed and a device registering with said counters when in zero position controlling the release of said lock.

37. In a voting machine, the combination with a series of counters arranged in 10 transverse rows and longitudinal columns, of a common testing device for all of said counters having parts adapted to register or interlock therewith when all of said counters are in zero position.

15 38. In a voting machine, the combination with a series of counters, and with means for locking said counters against operation, of testing means adapted to register or interlock with said counters when the latter are 20 in zero position, and devices for preventing the interlocking of said testing means and said counters when the latter are unlocked.

39. In a voting machine, the combination with a series of counters and with a lock for 25 holding said counters against operation, of a testing device arranged to register or interlock with said counters when the latter are in zero position, and interlocking parts interposed between said testing device and 30 said lock arranged to prevent the registering of said testing device and said counters when said lock is released.

40. In a voting machine, the combination with a series of counters, counter-controlling 35 mechanism, and a lock for said counter-controlling mechanism, of a testing device adapted to register or interlock with said counters when the latter are in zero position, and interengaging parts interposed between 40 said testing device and said lock arranged to prevent the registering of said testing device with said counters when said lock is released.

41. In a voting machine, the combination 45 with a series of counters and with a lock for holding said counters against operation, of a testing device adapted to interlock with all of said counters when the latter are in zero position, and means associated with 50 said testing device for preventing the release of said lock when said testing device is interlocked with said counters.

42. In a voting machine, the combination with a series of counters and with counter- 55 controlling mechanism, of a lock for said counter-controlling mechanism, and a testing device arranged to register or interlock with all of said counters when the latter are in zero position, said testing device being 60 arranged to prevent the release of said lock when it is interlocked with said counters.

43. In a voting machine, the combination with a series of counters and a lock for holding 65 said counters against operation, of a testing device adapted to register with all of

said counters when the latter are in zero position, and interlocking devices interposed between said testing device and said lock arranged to prevent the registering of said testing device and counters when said lock 70 is released and arranged to prevent the release of said lock when said testing device and said counters are in register.

44. In a voting machine, the combination with a series of counters, counter-controlling 75 mechanism, and a lock for said mechanism, of a testing device arranged to register with said counters when the latter are in zero position, said lock and said testing device having means associated therewith arranged 80 to prevent the registering of said testing device and said counters when said lock is released and arranged to prevent the release of said lock when said counters and said testing device are in register. 85

45. In a voting machine, the combination with a series of counters and a lock for holding 90 said counters against operation, of a testing device arranged to register with said counters when the latter are in zero position and to control the release of said lock, and interlocking parts between said testing device and said lock arranged to prevent the registering of said testing device and said counters when said lock is released. 95

46. In a voting machine, the combination with a series of counters, of a lock for holding 100 said counters against operation, of a testing device arranged to register with said counters when the latter are in zero position and to control the release of said lock, and means associated with said lock and said testing device arranged to prevent the registering of said testing device and said counters when said lock is released and arranged to prevent 105 the release of said lock when said testing device and said counters are in register.

47. In a voting machine, the combination with a series of counters and with a lock for holding 110 said counters against operation, of a device controlling the release of said lock, a testing device arranged to register with all of said counters when the latter are in zero position, said testing device being arranged to set said lock releasing device in operative 115 position and means interposed between and associated with said testing device and said lock arranged to prevent the registering of said testing device and said counters when said lock is released and to prevent the releasing of said lock when said testing device and said counters are in register. 120

48. In a voting machine, the combination with a series of counters and a lock for holding 125 said counters against operation, of a device arranged to positively interlock or register with said counters when in zero position, said device controlling the release of said lock, whereby the initial operation of said counters is prevented until they have been 130

returned to zero position, and means controlled by the initial operation of said counters for rendering said lock non-releasable.

49. In a voting machine, the combination with a series of counters, a lock for holding said counters against operation and mechanism controlling the operation of said counters, of a testing device adapted to positively interlock or register with said counters when the latter are in zero position, said testing device being arranged to control the release of said lock, and means controlled by the initial operation of said counter-controlling mechanism for rendering said lock non-releasable.

50. In a voting machine, the combination with a series of counters, mechanism controlling the operation of said counters, and a lock for said mechanism; of a testing device adapted to positively interlock or register with said counters when the latter are in zero position, a device controlling the release of said lock arranged to be set in operative position by said testing device, and means controlled by the initial operation of said counter-controlling mechanism for setting said release device in inoperative position.

51. In a voting machine, the combination with a series of counters, mechanism controlling the operation of said counters, and a lock for holding said mechanism against operation, of a testing device arranged to positively interlock or register with said counters when the latter are in zero position, and a device controlling the release of said lock interposed between said testing device and said counter-controlling mechanism and arranged to be shifted by said parts to its operative and inoperative positions respectively.

52. In a voting machine, the combination with a series of counters, a lock for holding said counters against operation, and means normally preventing access to said counters interlocked with said lock to compel the setting of the same when access is afforded to said counters, of a testing device adapted to positively interlock or register with said counters when the latter are in zero position, and means interposed between said testing device and said lock arranged to prevent the registering of said testing device and said counters when said lock is released.

53. In a voting machine, the combination with a series of counters, of a lock for holding said counters against operation, and means normally preventing access to said counters interlocked with said lock to compel the setting thereof when access is afforded to said counters, of a testing device adapted to positively interlock or register with said counters when the latter are in zero position, and means interposed between and associated with said setting device and said lock

arranged to prevent the registering of said testing device and said counters when said lock is released and to prevent the releasing of said lock when said testing device and said counters are in register.

70

54. In a voting machine, the combination with a series of counters, of a lock for holding said counters against operation, means normally preventing access to said counters interlocked with said lock to compel the setting thereof when access is afforded to said counters, of a testing device arranged to positively register or interlock with said counters when the latter are in zero position, said testing device controlling the release of said lock, whereby the initial operation of said counters after access is afforded thereto is prevented until said counters have been returned to zero position, and means controlled by the initial operation of said counters for rendering said lock non-releasable.

75

55. In a voting machine, the combination with a series of counters, of a lock for holding said counters against operation, and means normally preventing access to said counters interlocked with said lock and arranged to compel the setting thereof in operative position when access is afforded to said counters, of a testing device adapted to positively register or interlock with said counters when the latter are in zero position, a device controlling the release of said lock arranged to be set in operative position by said testing device, whereby the initial operation of said counters, after access is afforded thereto, is prevented until the counters have been returned to zero position, and means controlled by the initial operation of said counters for setting said releasing device in inoperative position.

90

56. In a voting machine, the combination with a series of counters, a lock for holding said counters against operation, mechanism controlling the operation of said counters, and means normally preventing access to said counters interlocked with said lock and arranged to compel the setting thereof in operative position when access is afforded to said counters, of a device arranged to positively interlock or register with said counters when the latter are in zero position, a device controlling the release of said lock arranged to be set in operative position by said registering device and means controlled by the initial operation of said operating mechanism for setting said releasing device in inoperative position.

95

57. In a voting machine, the combination with a series of counters, counter-controlling mechanism, a lock for holding said mechanism against operation, and means normally preventing access to said counters interlocked with said lock and arranged to compel the setting thereof in operative position when access is afforded to said counters, of a

100

testing device arranged to positively register or interlock with said counters when the latter are in zero position, a device controlling the release of said lock arranged to be set in operative position by said registering device and arranged to be set in inoperative position by the initial operation of said counter-controlling mechanism and means associated with said testing device and said lock

10 arranged to prevent the registering of said testing device and said counters when said lock is released.

58. In a voting machine, the combination with a series of counters, mechanism controlling the operation of said counters, a lock for said mechanism, and means normally pre-

venting access to said counters interlocked with said lock and arranged to compel the setting thereof when access is afforded to said counters, of a testing device adapted to 20 positively interlock or register with said counters when the latter are in zero position, and a device controlling the release of said lock, said device being set in operative position by said testing device and set in inoperative position by the initial operation of 25 said counter-controlling mechanism.
